Primary Examiner — Brian N. Vinson*(74) Attorney, Agent, or Firm* — Hodgson Russ LLP(57) **CLAIM**

The ornamental design for a light fixture, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front-top-left perspective view of a light fixture, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear-bottom-right view thereof;

FIG. 9 is a front-bottom-left perspective view thereof; and,

FIG. 10 is a rear-top-right perspective view thereof.

1 Claim, 10 Drawing Sheets**(10 of 10 Drawing Sheet(s) Filed in Color)**(56)
